UNITED STATES PATENT OFFICE.

FAY L. VAN DELINDER, OF CHICAGO, ILLINOIS.

DESIGN FOR A CANDY BOUQUET.

Application filed October 30, 1922. Serial No. 4,162. Term of patent 3½ years.

To all whom it may concern:

Be it known that I, FAY L. VAN DELINDER, a citizen of the United States, residing at Chicago, in the county of Cook and State of Illinois, have invented a new, original, and ornamental Design for Candy Bouquet, of which the following is a specification, reference being had to the accompanying drawing, forming part thereof.

I claim:

The ornamental design for a candy bouquet, as shown.

FAY L. VAN DELINDER.
